UNITED STATES PATENT OFFICE.

HENRY LEVINE, OF PHILADELPHIA, PENNSYLVANIA.

BOX.

Application filed August 17, 1921. Serial No. 492,929.

To all whom it may concern:

Be it known that I, HENRY LEVINE, a citizen of the United States, and a resident of Philadelphia, in the county of Philadelphia and State of Pennsylvania, have invented an Improvement in Boxes, of which the following is a specification.

My invention relates to boxes, particularly those made of pasteboard or other like more or less flexible material.

One of the objects of the invention is to provide a box consisting of a single integral sheet of material, such as pasteboard, having means whereby different parts thereof may be more securely interlocked or locked together than heretofore has been the case.

A still further object of the invention is to simplify and cheapen the construction of boxes of this character.

20 To these and other ends the invention comprehends the construction as hereinafter described in detail and particularly pointed out in the claims and as shown in the accompanying drawing, in which

25 Figure 1 is a plan view of a blank cut and shaped so that when folded it is adapted to produce a box embodying my invention;

30 Fig. 2 is a perspective view of a box formed from the blank shown in Fig. 1, but with the cover flaps in open position;

Fig. 3 is a central transverse sectional view showing the cover flaps in process of being closed and interlocked;

35 Fig. 4 is a perspective view of the box embodying my invention with the cover flaps in closed interlocked position; and

Fig. 5 is a longitudinal sectional view taken on the line 5—5 of Fig. 4.

Referring to the drawing: 1^a designates, as 40 a whole, a blank which is marked or creased along the dotted lines 1, 2, 3, 4, 5, 6, 7 and 8. It is along these lines that the blank is folded in the formation of the box, as shown in the subsequent figures of the drawing. The 45 portions 10 and 11 constitute the sides of the box, while the portions 12 and 13 constitute the ends thereof. Each of the sides 10 and 11 of the box is provided with narrow slots or slits 14 near opposite ends thereof.

50 Each of the ends 12 and 13 is provided with tapered extensions 15 at its opposite ends, which extensions are provided at their ends with lateral extending projections 16 forming ears. In forming the box, the sides 55 10 and 11 are first turned upwardly into position, substantially at right angles to the

portion 17 of the blank which constitutes the bottom of the finished box structure. Thereafter the ends 12 and 13 are turned upwardly and the extensions 15 thereof are folded over 60 the ends of the sides 10 and 11 and the T-shaped outer ends of the said extension 15 are inserted through the slots or slits 14. In order to facilitate the insertion of the outer T-shaped ends of the extension through the 65 said slots or slits 14, the projections or ears 16 are folded inwardly along the dotted lines 20. After they have been inserted, as described, the lateral projections or ears 16 are straightened out into the positions shown in 70 Figs. 4 and 5, so that thereby the ends of the box structure are securely interlocked with and fastened to the opposite ends of the sides 10 and 11 of the box structure.

After the sides and ends have been thus 75 secured together, the box may be then closed by means of the extensions 25 and 26 from the outer edges of the sides 10 and 11. Opposite end portions of the outer edge of the extension 25 extend inwardly from points 80 adjacent the outer ends thereof, as indicated at 27, and within the angle between the edges of said portions a tongue-like projection 28 is provided, having laterally projecting or extending ears 29 which are adapted 85 to be folded inwardly along the dotted lines 31, so as to overlap each other, as indicated in Fig. 2 of the drawing. The extension 25 is provided with a slit 32, the central intermediate portion of which extends in parallel 90 relation to the top edge of the side 10. At its opposite ends, the slit is provided with outwardly inclined extensions 33, so as to provide a short tongue-like portion.

The extension 26 is provided with a narrow 95 slot 35 through which the tongue-like extension 28 is adapted to be inserted. During the insertion of the tongue-like extension 28 through the said slit, the ears 29 are folded inwardly, so as to overlap each other 100 in the manner indicated in Fig. 2 of the drawing. The said tongue with the lateral projections 29 in folded, overlapped position with respect to each other is shown in Fig. 3 partially inserted through the slot 105 35. After the tongue-like extension 28 has been inserted through the slot 35, the lateral projections or ears 29 are straightened or flattened out, as indicated in Fig. 4 of the drawing, and are inserted through the slots 110 38 which are situated inwardly of and a short distance from the opposite ends of the

slot 35. These slots 38 extend transversely of the extension 26 and also transversely and in a direction transverse of the length of the adjacent side 11. For the purpose of facilitating the insertion of the projections or ears 29 into the said slits, the lower ends thereof are provided with angular extensions 39. After the tongue-like extension 28 has been inserted through the slot 35 and the 10 projections or ears 29 flattened out, as indicated in Fig. 4, the cover flaps 25 and 26 occupy horizontal positions; that is, positions substantially parallel with the bottom 17 of the box. In order to protect the outer 15 edge of the top flap 26, it is provided with a relatively narrow tongue or extension 40 which is adapted to be inserted through the slit 32, previously referred to and which is provided within the extension 25 near the 20 line of connection between the latter and the top edge of the side 10 of the box structure.

I have also provided extensions 41 at the outer edges of the ends 13 of the box structure, which extensions are adapted to be 25 folded inwardly in the completed box structure, as shown in Figs. 2 and 5 of the drawing. These extensions not only strengthen the ends of the box structure, but they also 30 cooperate with the opposite ends of the cover flaps 25 and 26 to form a more complete closure for the box.

It will be seen that I have provided a box structure in which the sides and ends and the cover flaps thereof are adapted to 35 be interlocked in such manner that they cannot accidentally become disengaged from each other.

It will also be seen that by my invention, I am enabled to produce a box of unusual 40 strength and neatness.

Although I have shown my invention as embodied in but a single form of construction, it will be understood that it is susceptible of embodiment in other forms and 45 that changes in the details of the construction may be made within the scope of the claims without departing from the said invention.

Having thus described my invention, what 50 I claim as new and desire to secure by Letters Patent is:

1. A box consisting of a single integral blank of flexible material having bottom, side, end portions and a cover comprising two 55 flap portions, the said side and end portions adapted to be bent into positions substantially at right angles to the said bottom

portion and means for securing the said side and end portions together and one of the said cover portions being provided with a tongue-like extension having laterally extending projections thereon and the other of said cover portions being provided with a narrow opening therein which extends in parallel relation to the edge of the side to which said portion is connected and other diagonally extending openings spaced from the opposite ends of said opening and the said tongue-like extension together with the lateral projections thereon being adapted to 60 extend from the underside of the said other cover portion through the said narrow opening and the said lateral projections on said tongue adapted to engage said diagonal openings, substantially as described. 75

2. A box consisting of a single integral blank of flexible material having bottom, side, end portions and a cover comprising two flap portions, the said side and end portions adapted to be bent into positions substantially at right angles to the said bottom portion and each of the end portions being provided at their opposite ends with tapered extensions which terminate in T-shaped heads and each of the side portions being provided near their opposite ends with narrow transversely extending openings through which the said T-shaped heads extend, whereby the said extensions are interlocked with the side portions of the box structure 80 and one of the said cover portions being provided with a slit intermediate its opposite edges and a tongue-like extension having laterally extending projections thereon, and the other of said cover portions being provided with a narrow opening therein which 85 opening extends in parallel relation to the edge of the side to which said portion is connected and other diagonally extending openings spaced from the opposite ends of said opening and the said tongue-like extension together with the lateral projections thereon being adapted to extend from the underside of said flap through the said narrow opening and the said lateral projections adapted to 90 engage said diagonal openings and the said other cover portion having a tongue expansion which is adapted to engage the said slit in the first named cover portion, substantially as described. 95

100 In testimony that I claim the foregoing as my invention, I have hereunto subscribed my name this 13th day of August, 1921.

HENRY LEVINE.
